UNITED STATES PATENT OFFICE.

EARL A. AVERILL, OF MOUNT VERNON, NEW YORK, ASSIGNOR TO LOCOMOTIVE FEED
WATER HEATER COMPANY, A CORPORATION OF DELAWARE.

LOCOMOTIVE FEED-WATER-HEATING SYSTEM.

Application filed June 23, 1920. Serial No. 391,009.

This invention relates to locomotive feed water heating systems and particularly to that class of systems which embodies a heater of the type known as a surface heater to which the feed water and the exhaust steam for heating the same are fed in independent currents, the exhaust steam condensing and draining from the heater through a suitable condensate drain or delivery pipe. The invention has especial reference to the location of the heater and to the handling and disposition of the condensate with a view to returning it to the feed water.

Among the objects of the invention is the provision of an arrangement which does not require an auxiliary lifting device for raising the condensate from the heater to the supply receptacle or tender. Another object of the invention is the provision of a feed water heating system, utilizing a heater of the character specified, in which the condensate from the heater is delivered directly into the suction line of the boiler feed pump instead of into the supply receptacle or tender.

A more specific object of the invention is the provision of a steam trap to prevent the possible entrance of air as well as of steam from the exhaust passages of the cylinders into the suction line of the boiler feed pump should, at any time, all the water be drawn from the condensate line.

Still another object of the invention is the provision of a suitable mixer for the condensate and the feed water.

These, together with such other objects as may hereinafter appear, or are incident to my invention I obtain by means of a construction which I have illustrated more or less diagrammatically in preferred form in the accompanying drawings, wherein

Figure 1 is a diagrammatical side elevation of a locomotive illustrating an embodiment of my improved feed water heating apparatus; Fig. 1^A is a detail section of the heater illustrating the various connections; Figure 2 is an enlarged, vertical, longitudinal section through the steam and air trap; Figure 3 is a section on the line 3—3 of Figure 2; and Figure 4 is an enlarged, vertical, longitudinal section through the feed water and condensate mixer.

Referring to the drawings and especially to Figure 1, it will be seen that I have lo-

cated a feed water heater 1, of the character above specified, on top of the smoke box 2 immediately in front of the stack 3. This location is, however, arbitrary, as the heater may be otherwise placed upon the boiler 4 as may be suitable or desirable. It is also not essential that it be placed on top of the locomotive although for the purposes of this installation it should be located at a point above the normal high level of the water in the supply receptacle or tender not illustrated. In the showing, exhaust steam from the cylinders is admitted to the heater through the inlet 6 and the gate valve 7. This steam, after it has heated the feed water, condenses and drains away through the condensate drain or delivery pipe 8. The exhaust steam from the boiler feed pump 9 is also delivered to the heater to aid in heating the water through the pipe 10, which pipe is provided with a suitable drain 11 controlled by a valve 12. The exhaust steam from other auxiliary devices, such as the air compressor for the brake system, not shown in this embodiment, may also be delivered to the heater if found convenient and desirable.

The feed water is delivered to the heater through the pipe 13 coming from the discharge side of the boiler feed pump 9. This water circulates through a series of tubes within the heater, the arrangement of which is illustrated in detail in Fig. 1^A, after which it passes out through the pipe 14 and is forced into the boiler through the boiler check valve 15, located immediately below the bell 16. The pipe 14 may be provided with a suitable drain connection 17 controlled by a valve 18. The suction line 19 of the boiler feed pump 9 is connected to the pipe 20 and in the feed water supply line formed by these two pipes I locate a condensate and feed water mixer 21. The condensate drain pipe 8 delivers the condensate from the heater into the feed water supply line at the point where the mixer is located.

In the condensate drain pipe are located a steam trap 22 and a filter 23, the steam trap being located on the heater side of the filter.

The filter is for the purpose of separating the oil from the condensate, more or less of which in this type of heater is always carried from the cylinders by the exhaust steam

in its passage to and through the heater. It is essential that this oil be removed before the condensate is returned to the feed water supply. It is not, however, the intention 5 in this invention to claim the filter in the arrangement shown, but I have found that it is difficult to obtain efficient functioning of the filter due to the fact that occasional quantities of steam pass down with the condensate through the pipe 8 which, upon entering the filter, destroy its ability to separate the oil from the water and carry the oil directly through the filtering elements. By means of the steam trap I am enabled to 10 overcome this difficulty and obtain efficient functioning of the filter. Whenever steam may attempt to pass from the heater through the condensate drain line 8 the trap 22 seals the passage to steam before it can enter the 15 filter.

The combined steam trap and air seal is illustrated in detail in Figures 2 and 3. The base casting 26 of this trap is arranged to admit the condensate through the inlet 27, 20 pass it through the balanced valve 28 and discharge it through the outlet 29. The valve is flexibly connected to a float 30 within the housing 31 which is provided with a small air vent 32.

Normally with condensate passing through the trap, the housing 31 is filled with water and the float rises to the top of its travel which lifts valve 28 from its seat leaving a free passage through the base 26. If the 30 supply of condensate should become exhausted and the suction of the boiler feed pump should tend to draw air or steam through the trap, the float would drop to seat the valve 28 and thereby seal the passage 35 through base 26. Thus, this valve performs the double function of preventing the entrance of steam into the filter and the entrance of air or steam into the suction line of the pump.

It will be noted that in the present installation the condensate from the heater is delivered directly into the suction line of the boiler feed pump and in such an arrangement, the suction line being directly connected to the supply receptacle, it is necessary 40 to provide some means for preventing the water in the supply receptacle from flowing out through the condensate drain line into the heater. If the heater were located below the level of the water in the supply receptacle, as is ordinarily the case, it would be necessary to accomplish this by the provision of a suitable check valve in the condensate delivery line. In view of the serious 45 results that would follow should the check valve not function properly, such as the loss of water without the knowledge of the engineer and the final backing up of water into the cylinders, I have found it best to locate 50 the heater at a point above the normal high

level of the water in the supply receptacle, as is illustrated. By so locating the heater it is impossible for the water from the supply receptacle to reach it through the condensate pipe.

The condensate and feed water mixer is illustrated in section in Figure 4 from inspection of which figure it will be seen that the cold feed water coming through the pipe 20 is thoroughly mixed with the condensate 75 coming from pipe 8. The action is somewhat in the nature of an injector inasmuch as the cold water is given as free passage through the mixer 21 as is possible so that the condensate is drawn into the mixer by 80 the suction action through the holes 33 in the cylindrical screen 34. The end of the screen 34 is open adjacent the suction line 19.

The operation of the system is as follows, assuming the locomotive to be running. Live 85 steam for the operation of the boiler feed pump 9 is delivered through the pipe 25, the exhaust of which, as previously pointed out, is delivered to the heater. Exhaust steam from the cylinders is admitted to the 90 heater through the gate valve 7 which, after accomplishing its function passes out in the form of condensate through the drain 8. Any steam which may work itself out of the 95 heater is caught in the trap 22, the oil is separated from the water in the filter 23 and the clean condensate is delivered to the mixer 21 in the feed water supply line. The boiler feed pump draws its supply through the pipe 19 and delivers it to the heater through the 100 pipe 13 from which it is conducted to the boiler 4 through the boiler check valve 15 by means of the connecting pipe 14.

Because the condensate coming from the heater is usually at a very high temperature 105 and, since it is delivered directly to the suction line of the pump, under such suction it might flash into the steam with very serious results to the operation of the pump and the locomotive. In order to avoid this 110 danger it is necessary that the condensate be thoroughly mixed with the incoming cold water from the supply receptacle. For this purpose I have provided the mixer 21 which should be connected to the supply receptacle 115 by a pipe of sufficient capacity to insure at all times the necessary flow of cold water. If this pipe from the supply receptacle be of this character and if it be at all times 120 clear of obstructions, it is not necessary that the mixer be of large size or capacity. A very small one in fact will answer the purpose such as is shown in Figure 1 and in detail in Figure 4. It is preferably that the mixer be located at a point below the 125 normal low level of the water in the supply receptacle.

I claim:

1. A feed water heating system for locomotives comprising in combination with the 130

- usual water supply system, a surface type feed water heater located on the locomotive at a point above the highest normal level of the water in the supply system, a boiler feed pump and connections for forcing water from the supply system through the heater and into the boiler, a connection between the steam space of the heater and the steam exhaust from the locomotive cylinders, a drain line connection between the steam space of the heater and the water supply system on the suction side of the boiler feed pump for delivering condensate back into the supply system, and a steam trap in said drain line. 25
2. A feed water heating system for locomotives comprising in combination with the usual water supply tank, a surface type feed water heater located on the locomotive at a point above the highest normal level of the water in the tank, a boiler feed pump and connections for forcing water from the tank through the feed water heater into the boiler, a connection between the steam space of the heater and the steam exhaust from the locomotive cylinders, a condensate and feed 30 water mixer in the connection between the pump and the tank, a drain line from the heater for delivering the condensate into the mixer, and a steam trap in said drain line. 35
3. A feed water heating system for locomotives comprising in combination with the usual water supply tank, a surface type feed water heater located on the locomotive at a point above the highest normal level of the water in the tank, a boiler feed pump and connections for forcing water from the tank through the feed water heater into the boiler, a connection between the steam space of the heater and the steam exhaust from the locomotive cylinders, a drain line from the heater for delivering the condensate into the mixer, and a steam trap in said drain line. 40
- In testimony whereof, I have hereunto 45 signed my name.

EARL A. AVERILL.

- usual water supply system, a surface type feed water heater located on the locomotive at a point above the highest normal level of the water in the supply system, a boiler feed 25
 5 pump and connections for forcing water from the supply system through the heater and into the boiler, a connection between the steam space of the heater and the steam exhaust from the locomotive cylinders, a drain line connection between the steam space 30
 10 of the heater and the water supply system on the suction side of the boiler feed pump for delivering condensate back into the supply system, and a steam trap in said 35
 15 drain line.
2. A feed water heating system for locomotives comprising in combination with the usual water supply tank, a surface type feed water heater located on the locomotive at a point above the highest normal level of the water in the tank, a boiler feed pump and connections for forcing water from the tank through the feed water heater into the boiler, a connection between the steam space of the heater and the steam exhaust from the locomotive cylinders, a condensate and feed 40
 20 water mixer in the connection between the pump and the tank, a drain line from the heater for delivering the condensate into the mixer, and a steam trap in said drain line.
- 20
- In testimony whereof, I have hereunto 45 signed my name.

EARL A. AVERILL.

Certificate of Correction.

It is hereby certified that in Letters Patent No. 1,585,226, granted May 18, 1926, upon the application of Earl A. Averill, of Mount Vernon, New York, for an improvement in "Locomotive Feed-Water-Heating Systems," errors appear in the printed specification requiring correction as follows: Page 2, line 108, strike out the article "the," and line 124, for the word "preferably" read *preferable*; and that the said Letters Patent should be read with these corrections therein that the same may conform to the record of the case in the Patent Office.

Signed and sealed this 22d day of June, A. D. 1926.
